UNITED STATES PATENT OFFICE

122,174

DESIGN FOR A COMBINED BENCH AND TABLE

Carroll C. Tabb, Shreveport, La., assignor to Frostbrand Furniture Mfg. Co., Shreveport, La., a corporation of Louisiana

Application April 1, 1940, Serial No. 91,381

Term of patent 14 years

To all whom it may concern:

Be it known that I, Carroll C. Tabb, a citizen of the United States, residing at Shreveport, in the Parish of Caddo and State of Louisiana, have invented a new, original, and ornamental Design for a Combined Bench and Table, of which the following is a specification, reference being made to the accompanying drawing, forming a part thereof, in which

Fig. 1 is a front elevational view of a combined bench and table embodying my new design;
Fig. 2 is a top plan view of the same; and
Fig. 3 is a side elevational view thereof.

I claim:

The ornamental design for a combined bench and table, substantially as shown.

CARROLL C. TABB.
